UNITED STATES PATENT OFFICE.

HOWARD J. MURRAY, OF BROOKLYN, NEW YORK.

ELECTRIC-CIRCUIT CONTROL.

1,288,128.

Specification of Letters Patent. Patented Dec. 17, 1918.

Application filed May 12, 1917. Serial No. 168,277.

To all whom it may concern:

Be it known that I, HOWARD J. MURRAY, a citizen of the United States, and resident of New York city, borough of Brooklyn, in the county of Kings and State of New York, have invented certain new and useful Improvements in Electric-Circuit Controls, of which the following is a specification.

My invention relates to circuit closures and circuit breakers of the types which are dependent for their actuation upon the acceleration or deceleration of the vehicle carrying the same and particularly relates to such a circuit closure constituting part of an automatically actuated signaling device for use on motor cars to indicate change in rate of travel.

In such devices now known, the opening or closing of the circuit is effected solely by the inertia forces which are due to changes in the movement of the body to which the device is attached. Such devices are obviously defective in that the duration of contact does not include the entire time of acceleration or deceleration and this defect is especially noticeable in a signaling device which with known types of circuit changing mechanism set up a quivering action, under those conditions where the deceleration or acceleration is not uniform.

Accordingly, one of the objects of my invention is to provide a simple means for changing the electric condition of a circuit, so as to control electrically operated mechanisms automatically from a change in velocity of moving parts carrying the contacts but which means is so arranged that it is possible to overlap the change of motion of the body to which the device is attached and thus steady the action of the signaling device.

This object is attained broadly by providing a relatively fixed and a movable contact mounted so that the closing of the contact by the inertia of the movable contact will bring into existence a second force designed to lightly hold the contact and to so regulate the engagement that the contact is effected only when a material change has occurred in the inertia factor controlling the movable contact. One means for effecting this result is to cause the movable contact to come under the influence of an electro-magnet so arranged that the magnet will either attract or repel the movable contact, as de-

sired, when acting under the force of its own inertia.

Various other objects and advantages of the invention will be in part obvious from an inspection of the accompanying drawings 60 and in part will be more fully set forth in the following particular description of one form of mechanism embodying my invention, and the invention also consists in certain new and novel features of construction 65 and combination of parts hereinafter set forth and claimed.

In the drawings:

Figure 1 is a vertical sectional view through a preferred embodiment of my invention; and

Fig. 2 is a diagrammatic view of the parts together with their electric connections.

In the following description and in the claims, parts will be identified by specific 75 names for convenience of expression but they are intended to be as generic in their application to similar parts as the art will permit.

In the drawings the parts are shown to be housed within a casing 3 designed to contain 80 all of the parts with the possible exception of the source of electric power and the manual controlled switches which may be used. This device is particularly designed to be mounted at the rear of an automobile for 85 the purpose of indicating a change in speed conditions of the vehicle. A relatively stationary contact 4 is fixedly mounted within the casing 3 and is preferably in the form of a set-screw threaded into a support 5, so 90 that the engaging end of the contact may be adjusted relative to the support and a nut-lock 6 may be used to lock the same in set position. A movable electric contact 9 contacts with contact 4 to complete the circuit 95 and actuate any device controlled thereby. The second contact is mounted for free movement toward its coacting contact in the direction paralleling the direction of travel of the vehicle as indicated by the arrow in 100 Fig. 1.

In some of the uses to which this device may be placed, it is desired to hold the contact in an inoperative position spaced from the fixed contact or it may be desired to 105 maintain the contact normally in circuit closing position, in either of which cases a spring 10 has one end affixed to the contact, or part carried thereby, and the other affixed to a stop member 11 to force the movable 110

contacts to or away from its coating fixed contact. The spring may be regarded either as a compression spring or a tension spring, depending upon the desired contact or non-
5 contractual relation of the contacts. The moving contact is shown mounted upon a pendulum 12, fulcrumed at a fixed support 13 and weighted by means of a weight 14 slidably adjusted along the length of the
10 pendulum.

The device is operatively connected to a source of energy 15 herein indicated diagrammatically by parallel power lines, one of which is connected by a conductor 16 to a
15 signaling device 17 herein shown to be an electric light lamp positioned within a reflector shell 18 constituting part of the casing 3. The opposite side of the lamp is connected by means of conductors 19 and
20 through manually controlled switches 20 and 21 to the other line of the source of electric energy. The circuits are so arranged that the switch 20 is normally opened as shown in the diagram but with the switch 21 in its
25 normally closed position, the closing of this switch 20 will complete the circuit through the lamp and magnet and thus manually actuate the signaling device.

As thus described, the device resembles a
30 similar construction constituting the subject matter of my co-pending application, Serial No. 12,100, filed Mar. 4, 1915.

In this construction the pendulum is also provided with an armature 22 operatively
35 disposed relative to the core 23 of an electro-magnet 24 carried within the casing 3, so that the closing of the circuit through the contacts 4 and 9 will energize the electro-magnet and cause its core to attract the
40 armature 22. The closing of the contacts 4 and 9 will energize the signaling device through the conductor 25, which leads from one side of the switch 21 to the pendulum and through a conductor 26 which leads
45 from the contact 4 to the conductor 19. One side of the electro-magnet is connected with the conductor 26 by means of a conductor 27 and the other side of the electro-magnet is connected to the conductor 16 by means
50 of a conductor 28 which contains in its circuit a variable resistance 29.

In operation, and assuming that the device is mounted upon a traveling vehicle and is suitably connected with its source of electric power and with the switch 21 closed and switch 20 opened, it will be evident that during the time while the vehicle is decreasing its rate of motion in the direction indicated by the arrow in Fig. 1, the weight 14 will
60 acquire motion in the direction indicated by the arrow, due to its inertia, which will tend to keep it moving at its original rate of motion. This motion will move the contact 9 into electric engagement with the contact 4
65 which will complete the circuit through the

electro-magnet and its core will attract the armature 22 attached to the pendulum. At the same time the circuit will be closed through the lamp 17 and the signal actuated.

By varying the resistance in the electro-magnet circuit, it is possible to vary the pull of the magnet on the pendulum. Let it be assumed that the resistance is so varied that the pull of the electro-magnet on its pendulum armature is equal to the force of gravity 75 tending to restore the weight 14 to its normal position, when both the casing and the weight 14 have no motion. This is also the condition when the motion of the casing or body to which it is attached and the weight 80 14 have acquired uniform constant motion, that is, when there is neither acceleration nor deceleration of the casing and its attached parts. If, under these conditions, the casing and its attached parts, decrease its rate 85 of deceleration, and due to the relative motion between the casing and the weight 14, the force tending to hold armature 21 against the core 22 decreases, and if the deceleration is sufficient, the weight 14 will 90 open the circuit and affect the signal such as to permit it to return to its normal position, even if the deceleration has not entirely ceased.

Should the pull of the magnet be equal 95 to the force of gravity acting on the pendulum, or perhaps slightly less, then the contacts 4 and 9 will be held together until deceleration has entirely ceased. In other words, the signal will continue to operate 100 until deceleration or acceleration has entirely ceased or the body has acquired approximately uniform constant motion.

By varying the resistance any desired holding effect may be produced even to the 105 extent of continually holding the contacts 4 and 9 in electric engagement.

While I have shown and described, and have pointed out in the annexed claims, certain novel features of my invention, it will 110 be understood that various omissions, substitutions and changes in the form and details of the device illustrated and in its operation may be made by those skilled in the art without departing from the spirit of the 115 invention.

Having thus described my invention, I claim:

1. In a device of the class described, the combination with a relatively fixed contact, a 120 second contact movable under the force of its inertia into position to affect its circuit closing relation with said fixed contact, means acting on the movable contact for affecting its circuit closing relation with the fixed contact, and means for moving said movable contact quickly into its inoperative position.

2. In a device of the class described, the combination with a relatively fixed contact, a second contact movable under the force of 125 130

its inertia into position to affect its circuit closing relation with said fixed contact and electro-magnetically actuated means governed by the relation of said contacts and 5 acting on the movable contact for affecting its circuit closing relation with the fixed contact.

3. A circuit closer including a relatively fixed contact and a movable contact coacting 10 with said fixed contact to make an electric engagement therewith, a plurality of power means for affecting said engagement, one of said means being actuated by the inertia of said movable contact and the other power 15 means being operatively responsive to the movement of said movable contact and acting to hold the movable contact in a preset fixed position.

4. In a device of the class described, the 20 combination with a relatively fixed contact, a second contact movable under the force of its inertia into position to affect its circuit closing relation with said fixed contact and locking means for holding the movable contact 25 in circuit closing position.

5. In a device of the class described, the 30 combination with a relatively fixed contact, a second contact movable under the force of its inertia into position to affect its circuit closing relation with said fixed contact, means for holding the movable contact in 35 circuit closing position and means acting on the movable contact tending normally to move the same into an inoperative position.

35 6. In a device of the class described, the combination with a relatively fixed contact, a second contact movable under the force of its inertia into position to affect its circuit closing relation with said fixed contact, 40 means for holding the movable contact in circuit closing position and adjustable means acting on the movable contact tending normally to move the same into an inoperative position.

45 7. In a device of the class described, the combination of a relatively fixed contact, a second contact movable under the force of its inertia into position to affect the electrical relation of said contacts and means for 50 holding said contacts in a preset relation, said movable contact being freely mounted so as to be promptly responsive to inertia forces imposed thereon.

8. In a device of the class described, the

combination of a relatively fixed contact, a 55 second contact movable under the force of its inertia into position to affect the electrical relation of said contacts, means for holding said contacts in a set relation and means for varying the holding effect of said contact-holding means.

9. In a device of the class described, the combination of a pendulum, a contact and an armature carried by said pendulum, an electromagnet coacting with said armature to 65 effect a movement of the pendulum, a second contact coacting with the contact on the pendulum to close the circuit through the electro-magnet.

10. In a device of the class described, the 70 combination of a pendulum, a contact and an armature carried by said pendulum, an electromagnet coacting with said armature to effect a movement of the pendulum, a second contact coacting with the contact on the pendulum to close the circuit through the electromagnet, and a rheostat for varying the electromagnetic action of the electromagnet 75 on the pendulum armature.

11. In a device of the class described, the 80 combination of a pendulum, a contact and an armature carried by said pendulum, an electromagnet coacting with said armature to effect a movement of the pendulum, a second contact coacting with the contact on the pendulum to close the circuit through the electro-magnet and an electric device actuated 85 by the closing of the circuit through said contacts.

12. In a device of the class described, the 90 combination of a pendulum, a contact and an armature carried by said pendulum, an electromagnet coacting with said armature to effect a movement of the pendulum, a second contact coacting with the contact on the pendulum to close the circuit through the electro-magnet, an electric device actuated by 95 the closing of the circuit through said contacts and a manually actuated switch for closing the circuit through said electric device independently of the closing of the circuit by said contacts.

Signed at New York city this 3rd day of May, A. D., 1917.

HOWARD J. MURRAY.
